ABSTRACT

An adaptive semiautomatic sewing system (10) comprises a sewing machine (12), a drive unit (42) including a variable speed motor and encoder for counting stitches sewn, at least one material edge sensor (40) mounted ahead of the needle (22) of the sewing machine, and a microprocessor controller (51) coupled to the sewing machine controls. The system (10) has manual, teach and auto modes of operation. In the teach mode, control parameters for each seam are stored as the operator sews the initial piece. Accurate control of seam lengths and end points is achieved by initiating countdown of a variable number of final stitches responsive to detection of the material edges by the sensors (40). In one embodiment, a window is set up around the stitch count at which terminal countdown initiates to avoid spurious signals. In another embodiment, momentary toggles of the sensors (40) are ignored so that an even wider range of sizes can be sewn with the same taught program.

CONTROL SYSTEM FOR SEWING MACHINE

CROSS-REFERENCE TO RELATED APPLICATION

This application is a continuation-in-part of copending application Ser. No. 168,525, filed July 14, 1980, now U.S. Pat. No. 4,359,953.

TECHNICAL FIELD

The present invention relates generally to a control system to adapt a sewing machine for semi-automatic operation. More particularly, this invention is directed to an adaptive sewing machine control system incorporating a microprocessor controller in combination with stitch counters and edge sensors to achieve more precise seam lengths and end points.

BACKGROUND ART

In the sewn goods industry, where various sections of material are sewn together to fabricate products, reasonably precise seam lengths and/or end points are often necessary for proper appearance and function of the finished products. Consider, for example, the collar of a shirt or other garment. The top stitch seam must closely follow the contour of the collar and terminate at a precise point. In the construction of shoes, accurate seam lengths must be maintained when sewing together the vamps and quarter pieces to achieve strength as well as pleasing appearance. Seams with imprecise lengths and/or end points can result in unacceptable products or rejects, thus causing waste and further expense.

Achieving consistently accurate seam lengths and/or end points at high rates of production, however, has been a long standing problem in the industry. Sewing machines traditionally have been controlled by human operators. Rapid coordination of the operator's eyes, hands and feet is necessary to control a high speed industrial sewing machine. Considerable practice, skill and concentration are required to sew the same type of seam with consistent accuracy time and time again.

Since such sewing operations tend to be repetitive and therefore lend themselves to automation, systems have been developed heretofore for automatically controlling sewing machines. U.S. Pat. Nos. 4,108,090, 4,104,976, 4,100,865 and 4,092,937 assigned to the Singer Company are representative of such devices. Each of these patents discloses a programmable sewing machine with three operational modes: manual, auto and learning. Control parameters are programmed into the system as the operator manually performs the initial sewing procedures for subsequent control of the sewing machine in the auto mode.

While these programmable sewing machines have several advantages over manually controlled machines, they are not without their disadvantages. The prior systems rely upon overall stitch counting to determine seam lengths and/or end points, variations in which can be caused by several factors. First, cloth or fabric is a relatively elastic material which can be stretched or contracted by the operator during the sewing procedure, thereby causing changes in average stitch lengths which can accumulate into a significant deviation over the length of a seam. Second, slippage can occur as the material is advanced between the presser foot and feed dog of the sewing machine, thereby causing further deviations in the length of the seam. Also, such slippage can vary in accordance with the speed of the sewing

machine. Third, any deviations between the paths of the desired seams versus the paths of the seams as programmed can also contribute to inaccurate seam lengths. Variations in seam lengths become greatest with long seams and elastic material.

Thus, although the programmable sewing machines of the prior art offer higher speeds of operation, they have not been satisfactory in those applications where precise seam lengths and end points are required.

10 Another approach to the problem of stopping a sewing machine precisely and consistently at a given point was proposed in an article entitled "Fluidics for the Apparel Industry", Journal of the Apparel Research Foundation, Vol. 3, 1969. It was proposed to mount a sensor in the presser foot of the sewing machine for sensing the edge of the material by which to initiate countdown of a preset number of stitches for stopping the machine at the desired point. This proposal, however, does not take into account the fact that edge conditions are dependent upon the seam and type of workpiece. No single preset number of stitches works well with pieces of different shapes or similar pieces of different sizes. As far as Applicants are aware, however, this proposal never has been embodied in a programmable sewing system.

A need therefore has arisen for an adaptive sewing machine control system utilizing a combination of stitch counting and edge detection techniques to obtain more accurate seam lengths and/or end points.

SUMMARY OF THE INVENTION

The present invention comprises a sewing machine control system which overcomes the foregoing and other difficulties associated with the prior art. In accordance with the invention, there is provided a system including a microprocessor controller which can be programmed with or taught a sequence of sewing operations by the operator in one mode, while sewing the initial piece, for automatically controlling the machine during subsequent sewing of similar pieces of the same or different sizes in another mode. The semi-automatic system herein does not rely upon either pure stitch counting or material edge detection alone, but rather utilizes a combination of these techniques together with other features to achieve more accurate seam length and end point control.

More specifically, this invention comprises a microprocessor-based control system for an industrial sewing machine. The system has manual, teach and auto modes of operation. In a first embodiment, one or more sensors are mounted in front of the presser foot for monitoring edge conditions of the material at the end of each seam. In the teach mode, operating parameters for each seam segment are programmed into the controller by the operator while manually sewing the first piece. For each seam, the number of stitches X sewn at the time of the last status change in the sensors, the sensor pattern or state after X stitches had been sewn, and the total number of stitches Y sewn in the seam are recorded along with sewing machine and auxiliary control inputs. In the auto mode, the number of stitches sewn in each seam is monitored as the count passes a window set up around X until the characteristic sensor pattern is seen, at which time Y-X terminal stitches are sewn to complete the seam.

The number of terminal stitches, as well as the point at which stitch countdown is initiated, can vary from

seam to seam such that the present control system is adaptive. Thus, more accurate seam lengths and/or end points are achieved by applying stitch counting to only a very small portion of the terminal end of each seam.

Several modifications for enhancing performance of the microprocessor-based control system herein are also disclosed. One modification relates to minimizing the number of slow stitches and achieving accurate needle positioning at the endpoint of each seam wherein the sewing speed profile, the total number of stitches Y, and the number of stitches Y-X sewn since the last status change in the sensors are recorded in the teach mode and utilized to compute the number of stitches M at which deceleration will be initiated for each seam. During playback in the auto mode, the microprocessor controller monitors the number of stitches sewn at a predetermined stopping speed of the sewing machine, i.e., the speed at which the machine can be stopped substantially instantaneously, and increments or decrements the value M according to whether the seam endpoint was overrun or underrun, respectively, such that the value of M is adaptively adjusted to minimize the number of stitches sewn at slow speed and thereby maximize the number sewn at high speed.

A second modification involves revision of the sensor logic to eliminate the window and thereby accommodate a wider variety of potential sewing conditions such that the endpoint of each seam is adaptively determined regardless of the size or accuracy of the piece.

Revision of the sensor logic to ignore status changes in the sensors which do not endure for more than a predetermined time interval, such as one stitch, comprises the third modification which functions as a filter against spurious signals.

Finally, yet another modification comprises one which allows the system to automatically compensate for the type of machine feed and to achieve, by means of an adaptive algorithm, improved seam length accuracy to plus or minus one-half stitch.

BRIEF DESCRIPTION OF DRAWINGS

A more complete understanding of the invention can be had by reference to the following Detailed Description in conjunction with the accompanying Drawing, wherein:

FIG. 1 is a perspective view of a programmable sewing system incorporating the invention;

FIG. 2 is a front view illustrating placement of the edge sensors relative to the sewing needle;

FIG. 3 is a sectional view taken along lines 3-3 of FIG. 2 in the direction of the arrows;

FIG. 4 is an illustration of the sensor mounting;

FIG. 5 is an illustration of a piece of material being provided with a seam by means of the invention;

FIG. 6 is a front view of an optional ply splitter;

FIG. 7 is an illustration of an alternative sensor;

FIG. 8 is a front view of the main control panel;

FIG. 9 is a front view of the auxiliary control panel;

FIG. 10 is a diagram of the control logic of the system in the teach mode;

FIG. 11 is a diagram of the control logic of the system in the auto mode;

FIG. 12 is a side view of a programmable sewing system according to the invention with an interface module for controlling auxiliary devices;

FIG. 13 is an illustration of a piece of material being provided with a double stitch pattern by means of the invention;

FIG. 14 is a diagram of a sewing speed profile for a seam;

FIG. 15 is an illustration of a patch pocket sewn to a pants panel;

FIGS. 16 and 17 are waveform diagrams illustrating the sensor status while sewing the seams of the patch pocket in FIG. 15;

FIG. 18 is a perspective view of the modified drive unit;

FIG. 19 is a diagram of the modified control logic of the system in the teach mode; and

FIGS. 20a and 20b are diagrams of the modified control logic of the system in the auto mode.

DETAILED DESCRIPTION

Referring now to the Drawings, wherein like reference numerals designate like or corresponding parts throughout the views, FIG. 1 illustrates a semi-automatic sewing system 10 incorporating the invention. System 10 is a microprocessor-based system which extends the capabilities of a sewing machine by enabling the operator to perform sewing procedures on a manual or semi-automatic basis, as will be more fully explained hereinafter.

System 10 includes a conventional sewing machine 12 mounted on a work stand 14 consisting of a table top 16 supported by four legs 18. Sewing machine 12, which is of conventional construction, includes a spool 20 containing a supply of thread for stitching by a reciprocable needle 22 to form a seam in one or more pieces of material. Surrounding needle 22 is a vertically movable presser foot 24 for cooperation with movable feed dogs (not shown) positioned within tabletop 16 for feeding material past the needle.

A number of standard controls are associated with sewing machine 12 for use by the operator in controlling its functions. A handwheel 26 is attached to the drive shaft (not shown) of machine 12 for manually positioning needle 22 in the desired vertical position.

Sewing speed is controlled by a speed sensor 15 which is actuated by a foot treadle 28, which functions like an accelerator. Vertical positioning of presser foot 24 can be controlled by heel pressure on foot treadle 28 which closes a switch 19 in speed sensor 15, which in turn causes the presser foot lift actuator 30 to operate. A leg switch 32 is provided for controlling the sewing direction of machine 12 by causing operation of reverse sew lever actuator 17. A toe switch 34 located adjacent to foot treadle 28 controls a conventional thread trimmer (not shown) disposed underneath the throat plate 36 of machine 12. Foot switch 38 on the other side of foot treadle 28 comprises a one-stitch switch for commanding machine 12 to sew a single stitch.

It will thus be understood that sewing machine 12 and its associated manual controls are of substantially conventional construction, and may be obtained from several commercial sources. For example, suitable sewing machines are available from Singer, Union Special, Pfaff, Consew, Juki, Columbia, Brother or Durkopp Companies.

In addition to the basic sewing machine 12 and its manual controls, system 10 includes several components for adapting the sewing machine for semi-automatic operation. A pair of sensors 40 are mounted in laterally spaced-apart relationship in front of needle 22 and presser foot 24. A drive unit 42 comprising a variable speed direct drive motor, sensors for stitch counting and an electromagnetic brake for positioning

of needle 22, is attached to the drive shaft of sewing machine 12. A main control panel 44 supported on a bracket 46 is provided above one corner of work stand 14.

On one side of work stand 14 there is a pneumatic control chassis 48 containing an air regulator, filter and lubricator for the sewing machine control sensors, pneumatic actuators and other elements of system 10. All of these components are of known construction and are similar to those shown in U.S. Pat. Nos. 4,108,090, 10 4,104,976, 4,100,865 and 4,092,937, the disclosures of which are incorporated herein by reference.

A controller chassis 50 is located on the opposite side of work stand 14 for housing the electronic components of system 10. Chassis 50 includes a microprocessor controller 51, appropriate circuitry for receiving signals for sensors and carrying control signals to actuators, and a power module for providing electrical power at the proper voltage levels to the various elements of system 10. The microprocessor controller 51 may comprise a Zilog Model Z-80 microprocessor or any suitable unit having a read only memory (ROM) and random access memory (RAM) of adequate storage capacities. An auxiliary control panel 52 is mounted for sliding movement in one end of chassis 50. Operation and function of the foregoing components will become more clear in the following paragraphs.

Referring now to FIGS. 2 and 3, further details of edge sensors 40 and their cooperation with needle 22 can be seen. If desired, only one edge sensor 40 can be used with sewing machine 12; however, complex shaped parts may require two or even three edge sensors located in laterally spaced-apart relationship in front of the needle. Sensors 40 can be mounted directly on the housing of sewing machine 12, or supported by other suitable means. As illustrated, each sensor 40 comprises a lamp/photosensor which projects a spot of light 40a onto a reflective strip 54 on throat plate 36. The status of each sensor 40 is either on or off depending upon whether the light beam thereof is interrupted, such as by passage of material over reflective strip 54 in the direction of arrow 56 in FIG. 3. Sensors 40 thus function to sense the presence of material being sewn and to signal the approach of the seam end by sensing passage of the trailing edge of the particular piece of material.

It will be appreciated that a significant feature of the present invention comprises usage of at least one and possibly a plurality of sensors 40 positioned in mutually spaced relationship ahead of needle 22 of sewing machine 12. Sensors 40 indicate whether or not the end of a particular seam is being approached. The condition of at least one sensor 40 changes as the trailing material edge passes thereunder to indicate approach of the seam end point. Sensors such as the Model 10-0672-02 available from Clinton Industries of Carlstadt, N.J., have been found satisfactory as sensors 40; however, infrared sensors and emitters, or pneumatic ports in combination with back pressure sensors could also be utilized, if desired. Any type of on/off sensors capable of detecting the presence or absence of material a preset distance in front of needle 22 can be utilized with apparatus 10 since the exact mode of their operation is not critical to practice of the invention.

Sensors 40 can be mounted directly on the housing of 65 sewing machine 12 or on a mounting assembly 58 as shown in FIG. 4. Assembly 58 includes a transverse support bar 60 to which is attached a mounting block 62

for each sensor 40. Mounting blocks 62, only one of which is shown, are slidable and rotatable relative to support bar 60, and can be secured in any desired position thereon by means of set screws 64. Each sensor 40 is attached to the end of a rod 66 slidably extending through its corresponding block 62 and secured in place by set screw 68.

Mounting assembly 58 thus facilitates adjustment of sensors 40 in the desired spaced relationship with respect to each other and with respect to sewing needle 22 in accordance with the shape of the material being sewn and other considerations of the particular sewing operation. Reflective tape 54, of course, could also be repositioned accordingly.

15 The operation and function of sensors 40 will be better understood upon reference to FIG. 5. Beginning at start point 70, a seam 72 is sewn along a piece of material 74 as the material is fed through sewing machine 12, which is not shown in FIG. 5, in the direction of arrow 76. Simultaneously, the number of stitches from start point 70 is being counted by the encoder within drive unit 42. Since reflective tape 54 is covered for a substantial portion of seam 72, the beams of sensors 40 are blocked and the conditions of both sensors are unchanged. At point 78 in seam 72, after X stitches have been sewn, one of the sensors 40 is cleared to change its condition thereby indicating approach of the end of the seam. Y represents the number of stitches sewn between start point 70 and end point 80 of seam 72. The value Y-X thus represents the number of stitches between points 78 and 80 for each seam.

30 The values X and Y along with the last change in condition of sensors 40 for each seam are stored and used by microprocessor controller 51 to control sewing machine 12 during operation of system 10 in the AUTO mode. Since the length of each seam and the boundary profile of the material following each seam may vary, it will be appreciated that the values X and Y change with the particular seam and workpiece being sewn such that 35 system 10 is adaptive. In addition to the more common devices found on a sewing machine, such as the presser foot lift actuator, reverse sew actuator and thread trimmer actuator, it will be appreciated that auxiliary devices including stackers, trimmers, guides and zig-zag lever actuators also can be controlled in this fashion as a function of stitch count and material edge detection.

Referring now to FIG. 6, the seam being sewn may not approach the boundary of the bottom ply of material in some procedures, such as when sewing a patch 50 pocket onto the front panel of a shirt. In such cases tape 54 can be positioned on a ply splitter or separator plate 82 positioned for passage between the upper and lower plies of material. Separator plate 82 can be attached to the housing of sewing machine 12 with a clamp band 84, or supported, in any other suitable manner. Use of separator plate 82 thus insures that the boundary of the relevant ply of material being sewn is properly sensed.

FIG. 7 illustrates an alternative approach to sensing the boundary of the relevant ply of material being sewn 60 which eliminates the need for a ply splitter or separator plate 82. If desired, each sensor 40 can comprise an infrared emitter 90 of adjustable radiation intensity positioned above an infrared sensor 92 mounted flush in the table top 16. This approach permits adjustment of the output of the infrared emitter 90 in accordance with the number of plies being sewn. For example, when sewing a single ply of material 94, the output of emitter 90 would be set to a relatively low level so that a single

layer of material would block sensor 92 and thereby change the condition of sensor 40. On the other hand, if a patch pocket or second ply of material 96 were being sewn onto a first ply of material 94, the energy output level of emitter 90 would be set to a relatively higher level sufficient to penetrate one ply of material but not two plies of material. Suitable infrared emitters and sensors are available from Spectronics, Inc. of Richardson, Tex. Use of such variable sensitivity sensors 40, such as IR emitters and sensors, thus lends additional flexibility to system 10.

The controls for sewing system 10, other than the manual controls associated with sewing machine 12, are found on operator or main control panel 44 and auxiliary control panel 52 shown in FIGS. 8 and 9. The primary controls are located on main panel 44 while auxiliary panel 52 contains adjustment controls. Panel 52 is normally closed within chassis 50, however, the panel can be pulled to an open position by means of handle 150 when adjustments are desired.

With reference to FIG. 8 in particular, main control panel 44 includes a power switch 154 to energize system 10. Switches 158, 156 and 160 are provided for respectively selecting the desired mode of operation. Lamps 156a, 158a and 160a are associated respectively with mode switches 156, 158 and 160 for indicating the particular mode selected.

A three-digit display 162 and associated switch 164 are provided for displaying the operator sewing efficiency being achieved or a predetermined error code upon detection of a malfunction. System 10 computes and displays the percentage sewing efficiency using as a reference the sewing time standard established for the particular sewing operation. Time lost for personal or delay reasons is also recorded and displayed. Switch 166 allows the operator to select the desired efficiency base with lamp 166a indicating selection of efficiency per bundle sewn, and with lamp 166b indicating selection of total efficiency for a desired period. Hold switch 168 can be moved to the delay or personal positions as indicated by lamps 168a and 168b, respectively, to interrupt computation of efficiency readings during thread breakage, machine delays, etc. Efficiency computation ceases while hold switch 168 is activated, and the amount of personal or delay time accumulated by the microprocessor controller 51 appears on display 162.

Switch 170 comprises an efficiency reset switch allowing the operator to clear and reset the sewing efficiency values. If switch 166 is set to bundle, activation of reset switch 170 will clear and reset only the bundle efficiency value and the total values will not be affected. If switch 166 is set to total, actuation of reset switch 170 will clear and reset both the bundle and total efficiency values.

Switch 172 on control panel 44 is provided for controlling the bobbin-monitoring capability of system 10. This is done by programming microprocessor controller 51 with the number of switches required to empty a full bobbin in sewing machine 12. Upon installation of a full bobbin, the operator can move switch 172 to the full position and then use sewing machine 12 in any one of the three modes. Upon depletion of the bobbin, switch 172 is then moved to the empty position to terminate counting with the number of stitches required to empty the bobbin. The microprocessor controller 51 thereafter monitors the number of stitches sewn and illuminates lamp 174 and activates a horn behind grill 176 on panel 44 when the stitch count reaches a predetermined per-

centage of the stored value to signal the need to change the bobbin.

Main control panel 44 also includes a one-stitch switch 182 to complement foot switch 38 shown in FIG. 1. Switch 182 can be used in any one of the three operational modes of system 10. Actuation of switch 182 will cause sewing machine 12 to sew a single stitch and leave needle 22 in the down position.

Referring now to FIGS. 8 and 9 together, system 10 includes several controls for further adjusting the operating characteristics of sewing machine 12. Switch 184 can be depressed in the auto mode of operation to modify acceleration and deceleration rates programmed into system 10 in the teach mode. When sewing in the auto mode with switch 184 actuated, which is indicated by lamp 184a, microprocessor controller 51 accelerates or decelerates sewing machine 12 via drive unit 42 in accordance with the rates programmed into system 10 in the teach mode. When switch 184 is not actuated, the acceleration and deceleration rates can be changed with rotary switch 186 located on auxiliary panel 52. In addition, a second rotary switch 188 located on panel 52 allows selection of the desired number of slow speed stitches at the beginning of each seam in the auto mode to reduce thread pull-out and other problems at the start of a seam. When switch 184 is reactivated in the auto mode, system 10 reverts to the acceleration rates originally programmed into microprocessor controller 51.

Switch 190 can be depressed in the auto mode of operation to modify sewing speeds programmed into system 10 in the teach mode. When switch 190 is activated in the auto mode, which is indicated by lamp 190a, the speed of the sewing machine 12 can be varied by operation of foot treadle 28. When switch 190 is deactivated, the foot treadle 28 acts as an on/off switch such that the speed of sewing machine 12 in the auto mode, with the foot treadle fully depressed, will follow the speed profile sewn in the teach mode. Rotary switch 192 permits the operator to select the amount of speed up in the auto mode over the speed profile programmed during the teach mode. In addition, a second rotary switch 194 permits selective reduction of the sewing pause and presser foot up time intervals over the programmed intervals.

Switch 196 permits the operator to regain manual control of sewing machine 12 in the auto mode of operation. System 10 utilizes a combination of stitch counting and edge detection techniques to control seam lengths and end points; however, there may be situations where the operator anticipates material handling or other difficulties with certain seams. Actuation of switch 196 in the auto mode, coupled with removal of pressure from foot treadle 28, causes system 10 to revert to the manual mode so that the operator can manually complete the seam. System 10 will remain in the manual mode until the operator can manually complete the seam and raise presser foot 24. When presser foot 24 is lowered again and foot treadle 28 is depressed, system 10 will automatically revert to the auto mode and resume sewing of the next seam as programmed. Depression of switch 186 in the teach mode functions to program a command into microprocessor controller 51 at that point along the seam to subsequently invoke the seam length control function in the auto mode so that the seam can be completed manually. Lamp 196a indicates actuation of switch 196.

Referring only to FIG. 9, auxiliary control panel 52 further includes a rotary switch 198 for reducing maxi-

mum speed of sewing machine 12 in the manual, teach, and auto modes of operation to facilitate the training of operators for system 10.

System 10 operates as follows. Actuation of switch 154 on control panel 44 energizes sewing system 10. Sewing machine 12 can be operated manually by depressing switch 160 and manipulating the hand wheel 26, foot treadle 28, and switches 19, 32, 34 and 38 to control the sewing machine. Foot treadle 28 functions as an accelerator in the manual mode to control the sewing speed of machine 12.

When it is desired to program system 10 with a particular sewing procedure, the teach mode of operation can be selected with switch 156. Typically, this is done before beginning a bundle of pieces of similar sizes and/or shapes. As the first piece is sewn manually by the operator, the microprocessor controller 51 records and stores the following:

- (a) number of stitches X and Y sewn in each seam and the status of sensors 40 at the end of the seam;
- (b) sewing speed for each stitch;
- (c) lifting and lowering of presser foot 24 as a function of stitch count;
- (d) time duration during which presser foot 24 is lifted;
- (e) operation of reverse sew switch 32 as a function of stitch count;
- (f) time duration of any pauses in the sewing operation;
- (g) actuation of the thread trimmer and thread wiper as a function of stitch count; and
- (h) actuation of a plurality of other auxiliary control devices, such as a zig-zag activation switch or throw-out mechanisms of split needle bar machines, as a function of stitch count.

This information is utilized by the microprocessor controller 51 to automatically control operation of sewing machine 12 in the auto mode of system 10. Single stitches sewn at the end of each seam by depression of one-stitch switch 38 or switch 182 are simply added to the taught stitch count. At the completion of each single stitch, needle 24 is left in the down position. Manually entered single stitches, but not the pauses therebetween, are added to the stored seam stitch count. Thus pauses between the single stitches manually entered in the teach mode are ignored by microprocessor controller 51 later in the auto mode such that sewing machine 12 continues at constant speed through the manually entered stitches and then stops, thereby facilitating the teaching of new operators.

After manual completion of the first piece, switch 158 can be actuated to place system 10 in the auto mode for semi-automatic sewing of the remaining pieces. The operator positions the next piece for sewing of the first seam thereof, and then depresses foot treadle 28 to initiate control of sewing machine 12 by the microprocessor. Foot treadle 28 in the auto mode simply functions as an on/off switch with operation of sewing machine 12 being controlled by microprocessor 51. Depression of foot treadle 28 thus causes repeat of the programmed sewing operation as the operator continues to handle and guide the material through sewing machine 12. In the auto mode, the microprocessor controller 51 does not slow sewing machine 12 or pause between stitches which were added in the teach mode by depression of one-stitch switches 38 or 182. Rather, a substantially constant sewing speed, as modified by switch 190, is maintained as the sewing machine approaches the end

of each seam, thereby saving considerable time. Release of foot treadle 28 interrupts the automatic sewing sequence.

A significant feature of system 10 is the fact that microprocessor 51 is programmed to set up a window in which the change in status of sensors 40 is expected, thereby eliminating spurious signals. For example, this window can be defined as 75-105% of the stitch count at the time of the last status change in sensors 40 before the end of the seam, which stitch count is represented by X in FIG. 5. Thus, microprocessor controller 51 does not begin to look for the characteristic pattern of sensors 40, and the controller is not responsive to a change in sensor status, until 75% of X stitches have been sewn. When sensors 40 change to their characteristic pattern for that seam, Y-X terminal stitches are sewn to end the seam at a precise point. If the characteristic sensor pattern is not detected within the window defined by 0.75X-1.05 X, microprocessor 51 automatically reverts to overall stitch counting for determining seam length and stops sewing machine 12 after Y stitches. Inaccuracies due to stitch counting therefore are reduced to a very small portion of the seam length.

It is advantageous to have a relatively wide window surrounding the stitch count at which a change in sensor status is expected. This permits system 10 to be programmed in the teach mode with a piece of given size to thereafter sew smaller size pieces of the same type in the auto mode without reprogramming the sewing operation. A relatively narrow window, such as 95-105% of X stitches works satisfactorily with pieces of the same size; however, since the transition to the characteristic pattern of sensors 40 on a relatively smaller piece of the same type might not appear in the window, the system would begin the countdown of Y-X stitches at the beginning of the window rather than at the point where the transition actually occurred resulting in an inaccurate seam end point. Thus, another aspect of the adaptive nature of semi-automatic sewing system 10 involves the fact that a sequence of sewing operations taught in the teach mode with a particular piece of one size can be utilized in the auto mode to sew similar pieces of other sizes without reprogramming.

Referring now to FIGS. 10 and 11, there are shown the flowcharts of the control logic utilized by sensors 40 in the teach and auto modes of system 10. In the flowcharts, the term sensor code means the on/off condition of sensors 40. The term stitch count means the number of stitches taken in a seam. The term sensor count means the number of stitches at the last change in the sensor code. The term window means the zone in which microprocessor 51 is looking for a sensor code corresponding to the programmed sensor code.

Referring to FIG. 10 in particular, the teach mode control logic for each seam begins at 200 by clearing the seam stitch count, sensor count and end tack flag. An inquiry is made at 202 whether a stitch has been taken. If no stitch has been taken, an inquiry is made at 204 whether a reverse command has been received by sewing machine 12. If no stitch has been taken and there has been no reverse command, an inquiry is made at 206 whether pressure foot 24 is up or whether the tread has been trimmed. If no stitch has been taken and there has been a reverse command, an inquiry about the stitch count is made at 208. If the stitch count is less than five the program proceeds directly to 206. If the stitch count is five or more, the end tack flag is set at 210 before proceeding to 206.

If a stitch has been taken, the stitch count is incremented at 212 before an inquiry about the stitch count is made at 214. If the stitch count is five or more, an inquiry is made at 216 as to whether the end tack flag is set. If the end tack flag is not set, fabric sensors 40 are read at 218 before an inquiry is made at 220 whether the condition or code of sensors 40 matches the previous code. If not, then the stored sensor code and sensor count are updated at 222 before proceeding to 204. Depending upon the position of pressure foot 24 or the status of the thread trimmer at 206, the program may go back to 202 or store the sensor code, stitch count and sensor count at 224 before returning to 200.

A sample program listing the microprocessor controller 51 of system 10 in the teach mode is set forth below. The program is particularly adapted for a Zilog Z-80 microprocessor, and is written in Z-80 assembly language in accordance with the Z-80 CPU Manual available from the Zilog Corporation. The program is subdivided into tables as follows:

TABLE		TEACH MODE PROGRAM

40

Referring particularly to FIG. 11, the control logic in the auto mode begins by clearing the seam stitch count at 230 before checking the sensor count at 232. If the sensor count is less than five, the window flag is set to zero at 234. If the sensor count is five or more, the window flag is set to one and the window count is set to 0.75 of the sensor count at 236. An inquiry is then made at 238 whether a stitch has been taken, and if not, the system continues looking for a stitch. If a stitch has been taken, the stitch count is incremented at 240 before checking the window flag at 242. If the window flag is zero and thus not equal to one, the stitch count is compared to the stored stitch count at 244, after which the program may go to 238 or 230. If the window flag equals one, the stitch count is compared to the window count at 246. Should the stitch count be less than the window count, the program then goes to 244. Should the stitch count be equal to or greater than the window count, sensors 40 are then read at 248 before comparing

45 the sensor code to the stored sensor code at 250. If the sensor code does not match the stored sensor code, the program proceeds to 244. Should the sensor code match the stored sensor code, the window flag is set to zero and the stitch count is set to the stored sensor count at 252 before proceeding back to 238.

50 A program listing for the microprocessor controller 51 of system 10 in the auto mode is set forth below. The program is particularly adapted for a Zilog Z-80 micro-processor, and is written in Z-80 assembly language in accordance with the Z-80 CPU Manual available from Zilog Corporation. The program is subdivided tables as follows:

TABLE	AUTO MODE PROGRAM

With reference to FIG. 12, there is shown an optional interface module 300 which can be incorporated into semi-automatic sewing system 10 herein to control auxiliary devices as a function of stitch count. Interface module 300 is coupled between the microprocessor controller 51 and the auxiliary device to be controlled. As illustrated, the interface module 300 includes six input channels 302-312 and six corresponding output channels 302a-312a. Some of the inputs and corresponding outputs can be connected to devices usually found on a sewing machine, such as the presser foot lift actuator, reverse sew actuator and thread trimmer actuator. The other inputs and corresponding output channels of interface module 300 can be utilized to control auxiliary devices such as stackers, trimmers, guides, zig-zag actuators, and so forth.

Under the control of microprocessor controller 51, interface module 300 receives command switch closure type input signals and generates appropriate output actuation signals. Thus, in the teach or manual modes, a device can be operated manually through the appropriate command switch. When a device is manually actuated in the teach mode, however, interface module 300 senses control inputs to the device and transmits corresponding signals which are stored in the microprocessor controller 51 as a function of stitch count. In subsequent playback of the programmed operation in the auto mode, actuation of the devices through module 300 will be controlled automatically by microprocessor controller 51.

More particularly, FIG. 12 illustrates interface module 300 in conjunction with a split needle bar, double needle sewing machine 314, which is mounted on table top 16 similar to single needle sewing machine 12 shown in FIG. 1. For purposes of clarity, the various standard controls associated with sewing machine 314 have been omitted from FIG. 12, however, it will be appreciated that many of these controls are the same as those of sewing machine 12 shown in FIG. 1. A pair of sensors 40 and associated retroreflective strip (not shown) are mounted on machine 314. Sewing machine 314 includes a left needle 316 with associated presser foot and a right needle 318 with associated presser foot. Needles 316 and 318 can be operated in unison or individually by manual actuation of conventional throwout mechanisms (not shown) connected to the needles. Suitable double-needle sewing machines, such as the Pfaff 542 or Juki LH-527, are commercially available.

A pair of actuators 320 and 322 are connected to the throw-out mechanisms of needles 316 and 318, respectively. A command switch 324 is connected between

20 the needle throwout actuators 320 and 322 and auxiliary input channels 308 and 310 of module 300. The corresponding output channels 308a and 310a are wired to the actuators 320 and 322. In the manual and teach modes, needles 316 and 318 can be thrown out as desired by manual operation of switch 324, however, in the teach mode an appropriate control signal is generated and transmitted by module 300 for storage in the microprocessor controller 51 as a function of stitch count. In the auto mode of system 10, operation of actuators 320 and 322 is controlled automatically by microprocessor controller 51 without stopping sewing machine 314.

FIG. 13 illustrates the operation of a semi-automatic sewing system 10 with double needle sewing machine 314 sewing a double seam around a corner of a piece 326. In the teach mode, from starting points 328, both needles 316 and 318 are positioned down and operate to sew parallel seams 330 and 332 along one edge of piece 326. At point 334, the right needle 318 is raised or thrown-out after R stitches have been sewn. Sewing is continued with the left needle 316 of sewing machine 314 through point 335, where the condition of sensors 40 change at X stitches, as was discussed in reference to FIG. 5, until stopping at point 336 after Y stitches. The values R and X could be the same or different, depending upon the particular seam and shape of material being sewn. Piece 326 is then turned before Z initial stitches are sewn by the left needle 316, such as by manipulation of the one-stitch switch, before stopping at point 338 along seam 330. When left needle 316 reaches point 338, the right needle 318 is lowered again at point 334 and sewing of seam 332 is resumed as the left needle continues from point 338 sewing seam 330. The values R, X, Y and Z along with the last change in condition of sensors 40 for each seam sewn in the teach mode are stored in microprocessor controller 51.

In the auto mode of system 10, the throw-out mechanism for right needle 318 is activated at stitch count R as the left needle 316 continues stitching. As soon as the characteristic sensor 40 pattern is seen in the window (0.75X-1.05X) surrounding X, Y-X terminal stitches are sewn before stopping at end point 336 in accordance with a combination of stitch counting and edge detection as described hereinbefore. With the double needle sewing machines of the prior art, it was necessary to stop the sewing machine at each of the points 334, 336 and 338 for the operator to manually raise or lower one of the needles; however, in the auto mode of the present invention, only the right needle is stopped at point 334 as sewing machine 314 continues to point 336.

Although control of the throw-out mechanisms of a double needle sewing machine has been illustrated by way of example, it will be understood that other types of auxiliary devices can be controlled in the same manner.

FIGS. 14-18 illustrate modifications which can be incorporated into system 10 to improve its performance. These modifications are primarily in the nature of programming and/or logic changes which improve the adaptability, reliability, accuracy and capability of system 10.

In particular, those skilled in the art will appreciate the fact that a certain period of time or number of stitches is required to bring the sewing machine 12 to a precise stop from a high rate of speed. The amount of time or number of stitches required depends upon several factors including the speed of the machine and its inertia, the material type and weight, the thread type and weight, etc. Deceleration of the sewing machine 12 must be initiated at the proper time to prevent overrunning the desired seam end point, but premature deceleration can result in wasted time which is cumulative. Further, it is desirable to halt the drive unit 42 at a precise point in the rotational cycle of machine 12 to achieve the desired position (up or down) of needle 22. The microprocessor controller 51 could be programmed to initiate deceleration of machine 12 at a fixed preset number of stitches before the end of each seam; however, for seams of relatively short lengths where the sewing machine would not be operating at top speed, premature deceleration and thus wasted time would result. It is therefore desirable to maximize the time during which machine 12 operates at its highest speed and to adaptively control the point at which deceleration commences to minimize the number of slow stitches sewn at the terminal end of each seam.

FIG. 14 illustrates a typical sewing speed profile for a seam sewn in accordance with the modified logic explained below. In the teach mode, the microprocessor controller 51 of system 10 measures and stores the sewing speed profile or speed per stitch, the total number of stitches Y sewn, and the number of stitched Y-X sewn after the last status change in sensors 40 for each seam. These values are used by the microprocessor controller 51 in the auto mode to compute the adaptive number of stitches M before the end of each seam at which to initiate deceleration from the high speed of operation, such as 2000-5000 rpm, represented by line 350.

During playback in the auto mode, the microprocessor controller 51 initiates deceleration of the motor end drive unit 42 and monitors the number of stitches sewn at the "stopping" speed represented by line 352. As used herein, the stopping speed means a speed such as 300 rpm from which sewing machine 12 can be halted substantially instantaneously. One stitch or less at the stopping speed represented by line 352 is considered acceptable, however, if the microprocessor controller 51 measures that more than one stitch was sewn at the stopping speed, the stored value M is decremented by the excess number of slow stitches sewn. If, on the other hand, the microprocessor controller 51 measures that too many stitches were sewn and that the seam end was overrun, the stored value M is increased. The stored value M for each seam is thus adaptively adjusted during each sewing operation to maintain the number of stitches sewn at 65 the slow speed to one stitch or less.

In the first embodiment of the invention, a window of 0.75X to 1.05X, for example, was set up around the

number of stitches X sewn at the time of the last status change or "toggle" in the sensors 40 in order to eliminate spurious signals. This logic works well with pieces of slightly different sizes, but has been found to be a limiting factor when sewing pieces of substantially smaller or larger sizes wherein the requisite sensor state may not appear in such a window. Also, the logic of storing only the last sensor condition for comparison in determining the end point of each seam may not be accurate for all sewing operations. It is thus desirable to completely eliminate the window wherein the characteristic sensor pattern is expected so that a wide range of part sizes as well as inaccurately cut parts can be sewn using the same taught program, and to revise the sensor logic so that it does not rely simply on the last sensor pattern to initiate seam termination and can therefore accommodate a wider variety of sewing operations.

FIG. 15 shows a sewing operation which illustrates the advantages of the revised sensor logic described more fully hereinafter. When a patch pocket 354 is set on a pants panel 356, a riser or yoke 358 is sometimes provided above the pocket usually for purposes of style. When sewing the right-hand and bottom seams in the directions respectively indicated by arrows 360 and 362, the sensor state contains one change or toggle as represented by FIG. 16. However, when sewing the left-hand seam in the direction of arrow 364, the sensor 40 toggles more than once as represented by FIG. 17 as it senses the boundary of pocket 354 and then yoke seam 359. Although the last sensor status is correct, it references the yoke seam 359 instead of pocket 354. Thus, reliance can be placed on the last sensor state for terminating the right-hand and bottom seams, but not for terminating the left-hand seam.

In accordance with the revised logic of this modification, the status changes or toggles of sensors 40 for each seam are stored by the microprocessor controller 51 in the teach mode. During playback in the auto mode, the microprocessor controller 51 is programmed to compare the sensor toggles with the stored toggle history for that seam as each seam is being sewn so that, once the proper toggle sequence has been achieved, countdown of Y-X terminal stitches can be initiated to complete the seam. The toggle sequences programmed into system 10 in the teach mode are thus utilized to control seam lengths and end points in the auto mode.

As explained above in connection with FIG. 14, the revised logic provides for adaptive adjustment of the number of stitches before the end of each seam at which deceleration of sewing machine 12 is initiated to prevent overrunning the seam end points. If the last toggle condition of sensors 40 occurs such that the stored value M is less than the value of Y-X stitches stored in microprocessor controller 51, the logic also provides for decrement back to the previous sensor toggle point as the basis for terminating the seam in the auto mode. For example, in the case of the left-hand seam on the patch pocket 354 shown in FIG. 15, the last off/on toggle on the far side of yoke seam 359 would be checked and determined to afford insufficient time to decelerate sewing machine 12. The microprocessor controller 51 would then automatically go back to the on/off sensor toggle at the front edge of yoke seam 359 and check again if a sufficient number of stitches remained to decelerate sewing machine 12 to a precise stop, and, if not, the controller would then back up once again to the off/on toggle occurring at the pocket boundary as the basis for terminating the seam.

If there is only one sensor toggle along a seam, such as the right-hand and bottom seams of the patch pocket 354 in FIG. 15, and an insufficient number of stitches remain in the seam to properly decelerate sewing machine 12, the seam will be sewn in the auto mode as programmed but an error code will appear on the main control panel 44 indicating that the dynamic capabilities of system 10 had been exceeded.

A further revision to the sensor logic comprises checking the sensor condition at the start of each seam in the auto mode against the stored sensor condition programmed in the teach mode. If the sensed and stored initial sensor conditions are not the same, the system 10 reverts to pure stitch counting to determine the seam length and end point. This feature is particularly useful for very short seams where the condition of sensors 40 may not consistently be the same due to irregularities in the material, etc.

As stated above, the revised sensor logic eliminates the use of a window around the adaptive value of X stitches for each seam. The purpose of this window was to avoid picking up spurious signals from false sensor toggles which could prematurely initiate termination of a seam. To provide noise protection for sensors 40, the sensor logic can also be revised to include the requirement that sensor toggles must last for more than one stitch before the microprocessor controller 51 will respond to such toggles. Momentary sensor toggles which endure for less than one stitch are thus filtered out as spurious signals.

Another important feature represented by the modified control logic for system 10 comprises enhancement of the seam length accuracy from ± 1 stitch to ± 0.5 stitch. It will be appreciated that a status change or toggle of sensors 40 can occur anytime during the one revolution of the motor within drive unit 42 required to form a stitch. A ± 1 stitch accuracy is obtained when sensors 40 change state immediately before or immediately after the needle position where the microprocessor controller 51 recognizes such changes. It will further be appreciated that many sewing machine feed mechanisms only advance material over a portion of the stitch forming cycle. For example, in a needle feed machine, advancement of the material occurs when the needle is in the material. Material advancement is continuous and uniform throughout the complete stitch forming cycle in a continuous feed machine. It is thus desirable to be able to read sensors 40 more than once during each stitch cycle and to compensate for the particular material feed characteristics for the sewing machine 12.

FIG. 18 shows an exploded perspective illustration of the modified drive unit 366 which can be utilized in system 10. Drive unit 366 includes a housing 368 enclosing a variable speed drive motor 370 having a drive shaft 372 coupled directly to the drive shaft of sewing machine 12. An electromagnetic brake 374 is secured to shaft 372 as are a sensor vane 376 and the hand wheel 26, which has been omitted from FIG. 18 for clarity. The sensor vane 376 includes a plurality of uniformly spaced openings therearound which cooperate with sensors 378 and 380 to provide a more precise measurement to the microprocessor controller 51 of the angle in the sewing cycle at which each status change in sensors 40 occurs. As illustrated, sensor vane 376 includes 36 evenly spaced circumferential openings therein to achieve a resolution of 10° . Sensor 378 provides a reference or sync signal against which the motor angle sig-

nals from sensor 380 are compared within microprocessor controller 51 to fix the angular position in the sewing machine cycle, and thus the needle position, where each toggle of edge sensors 40 occurs.

Any suitable interrupt type sensors can be used for sensors 378 and 380. For example, a Model TIL 147 photoptical sensor from Texas Instruments Corporation can be used for sensor 380. A Model TL 172C hall effect sensor from Texas Instruments Corporation can be used for sensor 378.

Since a change of state or toggle of sensor 40 is transmitted to the microprocessor controller 51 via an interrupt channel thus providing an immediate indication of the sensor change relative to the stitch forming cycle, the microprocessor controller can be programmed with an algorithm for deciding whether a stitch should be added or deleted at the end of the seam. The algorithm for determining the number of stitches to be sewn after the relevant sensor toggle is as follows:

Y = number of stitches to be sewn after sensor changes state or toggles;

Sew Y stitches if $|\phi_{auto} - \phi_{teach}|$ is less than Δ .

Sew $Y+1$ stitches if $(\phi_{auto} - \phi_{teach})$ is greater than Δ .

Sew $Y-1$ stitches if $(\phi_{auto} - \phi_{teach})$ is less than Δ .

Where: ϕ_{stop} = angle at which material feed stops during the sewing cycle;

ϕ_{start} = angle at which material feed starts;

$\Delta = (\phi_{stop} - \phi_{start})/2$;

ϕ_{teach} = angle at which sensor toggles in the teach mode;

ϕ_{auto} = angle at which sensor toggles in the auto mode.

In order to use the foregoing algorithm correctly, system 10 must be provided with the particular material feed characteristics of sewing machine 12. One way to provide this information to microprocessor controller 51 is to input the angles ϕ_{start} and ϕ_{stop} via the keyboard 167 on auxiliary control panel 52. Another way to do this would be to provide a calibration software routine for the microprocessor controller 51 which would enable it to self calibrate and automatically determine the ϕ_{start} and ϕ_{stop} values for a given machine and stitch length setting.

Referring now to FIGS. 19 and 20a and b, there are shown the flow charts for the control logic utilized by sensors 40 in the modified teach and auto modes of system 10. The meanings of the variables are as follows:

T = no. of taught sensor toggles in the teach mode.

Y = no. of sensed stitches sewn in the teach mode after the last sensor toggle.

DT = taught angle of motor 370 at which final sensor toggle occurred in the teach mode.

DA = sensed angle of motor 370 at which final sensor toggle occurred in the auto mode.

DS = angle of motor 370 at which stitch formation begins.

DE = angle of motor 370 at which stitch formation terminates.

D1 = $(DE - DS)/2$.

M = seam stopping variable.

Referring to FIG. 19 in particular, the teach mode control logic for each seam begins at 390 with the command to sew the next seam after which sensors 40 are enabled at 392. The values T, Y and N are then set to zero at 394.

An inquiry is then made at 396 whether foot treadle 28 is down. If so, the logic proceeds to 398 where a

stitch is sewn and Y is incremented. If foot treadle 28 is not down, an inquiry is made at 400 whether Y is less than 5. If Y is greater than or equal to 5, the values T, Y and DT are stored at 402 before returning to 390. If Y is less than 5, an inquiry is made at 404 whether T is greater than 1, and, if not, the logic proceeds to 402. If T is greater than 1, T is decremented and Y is set to YT + Y at 406 before returning to 400.

If foot treadle 28 is down, another stitch is sewn and Y is incremented at 398 before an inquiry is made at 408 whether there has been a change of state or toggle of sensors 40 since the last logic loop. If there has been no sensor change, an inquiry is made at 410 whether N=1, and, if not, another inquiry is made at 396. If N does equal one, YT is set to Y, T is incremented, and Y and N are set to zero at 412 before proceeding to 396 where the up or down position of foot treadle 28 is checked.

If there has been a sensor change at 408, and inquiry is made at 414 whether N=1. If N is not equal to 1, N is set to 1 at 416 and DT is set to the motor angle before returning to 396. If N does equal 1, N is set to zero at 418 and a command is given to ignore the one stitch sensor toggle before returning to 396.

Referring particularly to FIGS. 20a and b, the control logic in the auto mode begins at 420 by setting the variables N, L and K to zero. At 422 a command is given to sew the next seam after which an inquiry is made at 424 whether it is the first time that seam is being sewn. If so, M is set to Y-1 at 426 before proceeding to 428. Thus, the seam stopping variable M is initially set to one stitch less than the taught number of stitches between transition of sensors 40 and the seam end point for the first time that seam is sewn in the auto mode. If it is not the first time that seam is being sewn, the logic proceeds directly from 424 to 428.

After the next stitch has been sewn at 428, an inquiry is made at 430 whether there has been a change of state or toggle in sensors 40 since the last stitch. If so, an inquiry is made at 432 whether N equals one. If not, then at 434 N is set to one and DA is set to the motor angle before returning to 428. If N does equal one, then N is set to zero and the one stitch toggle is ignored at 436 before returning to 428. A sensor change on each of two consecutive stitches thus indicates a momentary or false toggle of sensors 40.

If there has been no sensor change, an inquiry is made at 438 whether N equals one. If not, then another stitch is sewn at 428. If N does equal one, L is incremented at 440. L corresponds to the number of sensor toggles sensed in the auto mode. Then an inquiry is made at 442 whether L equals T. If not, N is again set to zero at 444 before sewing another stitch at 428. If L equals T, which means that the taught and sensed toggle histories for that seam correspond, Y is decremented at 446 to subtract the stitch count registered after sensors 40 changed state.

After 446, an inquiry is made at 448 whether the absolute value of DA minus DT is less than DI. If not, another inquiry is made at 450 whether the difference between DA and DT is less than minus DI. If the answer to the inquiry of 450 is yes, Y is decremented at 452 before proceeding to 454. If the answer to the inquiry of 450 is no, another inquiry is made at 456 whether the difference between DA and DT is greater than DI. After 456, the logic proceeds to 454, however, Y is first incremented at 458 if the answer to the inquiry

is yes. Decisions 448, 450 and 456 thus comprise the algorithm by which the microprocessor controller 51 determines how many terminal stitches to take after transition of sensors 40.

If the absolute value of the difference between DA and DT is less than DI, then Y-M additional stitches are sewn and Y is set to M at 454 before dynamic braking is applied at 460. An inquiry is then made at 462 whether a stitch has been taken, and, if not, another such inquiry is made. If a stitch has been taken, K is incremented at 464 to keep track of the number of stitches sewn after braking started before an inquiry is made at 466 whether sewing machine 12 has stopped. If the sewing machine has not stopped, the logic returns to the inquiry of 462. If the sewing machine has stopped, an inquiry is made at 468 whether K matches Y. If K equals Y, the logic returns to 420. If K does not equal Y, an inquiry is made at 470 whether K is less than Y. If K is less than Y, indicating that braking started too soon, Y-K additional stitches are sewn at 472 and M is decremented at 474 before returning to 420. Thus, the seam stopping variable M is monitored and adaptively adjusted, if necessary, each time the seam is sewn in the auto mode. If K is not less than Y, indicating that the dynamic capabilities of system 10 have been exceeded, an error code is generated at 476 and M is incremented at 478 so that braking is initiated sooner before returning to 420.

A program listing, with comments, for the microprocessor controller 51 of system 10 in the modified teach and auto modes discussed above is set forth in Table 7 below. The program is particularly adapted for a Zilog Z-80 microprocessor, and is written in Z-80 assembly language in accordance with the Z-80 CPU manual available from Zilog Corporation.

In view of the foregoing, it will be apparent that the present invention comprises an adaptive sewing machine control system having significant advantages over the prior art. The system herein utilizes a combination of stitch counting and edge detection to achieve precise seam lengths and end points. A sensor is located ahead of the sewing needle for detecting the approach of the material boundary following each seam. Most of the operations of the sewing machine are controlled by the microprocessor as a function of stitch count, however, the only stitch counting that is utilized to determine seam length comprises a relatively small variable number of stitches at the end of each seam. Countdown of the variable terminal number of stitches can be initiated by correspondence of the taught and sensed final toggle conditions or correspondence of the taught and sensed toggle histories. Spurious signals which could cause premature initiation of the final stitch countdown are avoided either by setting up a window around the stitch count corresponding to the last change in sensor condition before the end of the seam, or by ignoring momentary toggles of the edge sensors. Other advantages will be apparent to those skilled in the art.

Although particular embodiments of the invention have been illustrated in the accompanying Drawing and described in the foregoing Detailed Description, it shall be understood that the invention is not limited only to the embodiments disclosed, but embraces any alternatives, equivalents, modifications and/or rearrangements of elements as fall within the scope of the invention as defined by the following claims.

We claim:

1. In a semi-automatic sewing system including a sewing machine with a reciprocal needle for stitching material advanced in a feed direction and controls for operating said sewing machine, with means for counting stitches being sewn and with sensors for detecting manipulation of the sewing machine controls, the improvement which comprises:
  - means mounted in spaced relationship with said needle for sensing the material periphery following a seam; and
  - a microprocessor controller with plural operational modes coupled to said sewing machine controls and responsive to said stitch counting means and said material sensing means;
  - said microprocessor controller in one mode being operable to record for each seam the operational input sequence of said sewing machine controls as a function of stitch count, the sewing speed for each stitch sewn, the toggle history of said material sensing means, and a variable number of terminal stitches between detection of the material periphery by said material sensing means and the endpoint of said seam;
  - said microprocessor controller in another mode being operable to generate output control signals for said sewing machine to initiate countdown of said variable number of terminal stitches upon detection of the material periphery by said material detection means and upon correspondence of the sensed and stored sensor toggle histories for each seam, wherein said microprocessor controller in said another mode is responsive to said material detection means only for sensor toggles which last more than a preprogrammed few number of stitch counts to avoid spurious signals.
2. The semi-automatic sewing system of claim 1, wherein said material sensing means comprises at least one on/off sensor located ahead of said needle in a direction opposite the material feed direction.
3. The semi-automatic sewing system of claim 1, wherein said material sensing means comprises an infrared emitter of variable output and an associated sensor located ahead of said needle in a direction opposite the material feed direction.
4. The semi-automatic sewing system of claim 1, wherein said microprocessor controller in said one mode stores the total number of stitches required for each seam, and wherein said microprocessor controller in said other mode reverts to said total stitch count for determining seam length absent detection of the material periphery and correspondence of the sensed and stored toggle histories of said material sensing means.
5. In a semi-automatic sewing system including a sewing machine with a reciprocal needle for stitching material advanced in a feed direction and controls for operating said sewing machine, with means for counting stitches being sewn and with sensors for detecting manipulation of the sewing machine controls, the improvement which comprises:
  - means mounted in spaced relationship with said needle for sensing the material periphery following a seam; and
  - a microprocessor controller with plural operational modes coupled to said sewing machine controls and responsive to said stitch counting means and said material sensing means;
  - said microprocessor controller in one mode being operable to record for each seam the operational input sequence of said sewing machine controls as a function of stitch count, the sewing speed for each stitch sewn, and a variable number of terminal stitches between detection of the material periphery by said material sensing means and the endpoint of said seam;
  - said microprocessor controller in another mode being operable to generate output control signals for said sewing machine to initiate countdown of said variable number of terminal stitches upon detection of the material periphery by said material detection means, wherein said microprocessor controller in said another mode monitors the stitches sewn during deceleration of the sewing machine to a seam endpoint and adaptively adjusts the point at which deceleration is initiated in order to minimize the number of slow stitches at the end of each seam.
  - 6. The semi-automatic sewing system according to claim 5, wherein said microprocessor controller in said other mode further compares the adaptive number of stitches required to decelerate said sewing machine to a

precise stop with the number of stitches remaining to be sewn in the seam and utilizes, as a basis for terminating the seam, the last toggle point of said material sensing means which provides a sufficient number of stitches to decelerate and halt said sewing machine.

7. In a semi-automatic sewing system including a sewing machine with a reciprocal needle for stitching material advanced in a feed direction and controls for operating said sewing machine, with means for counting stitches being sewn and with sensors for detecting manipulation of the sewing machine controls, the improvement which comprises:

means mounted in spaced relationship with said needle for sensing the material periphery following a seam;

a microprocessor controller with plural operational modes coupled to said sewing machine controls and responsive to said stitch counting means and said material sensing means;

said microprocessor controller in one mode being operable to record for each seam the operational input sequence of said sewing machine controls as a function of stitch count, the sewing speed for each stitch sewn, the toggle history of said material sensing means, and a variable number of terminal stitches between detection of the material periphery by said material sensing means and the endpoint of said seam;

said microprocessor controller in another mode being operable to generate output control signals for said sewing machine to initiate countdown of said variable number of terminal stitches upon detection of the material periphery by said material detection means and upon correspondence of the sensed and stored sensor toggle histories for each seam;

means for substantially continuously sensing the position of the reciprocal needle of said sewing machine;

said microprocessor controller being responsive to said needle position sensing means, and being further operable in said one mode to record the point in the relevant needle reciprocation at which each toggle of said material sensing means occurs; and said microprocessor controller being further operable in said another mode to adaptively adjust said terminal number of stitches for each seam in accordance with the sensed point in the relevant needle reciprocation at which the seam-termination toggle of said material sensing means occurs in order to improve seam length accuracy.

8. The semi-automatic sewing system according to claim 7, wherein said microprocessor controller in said other mode further compensates for the type of material feed characteristics of said sewing machine.

9. A semi-automatic sewing system, comprising:

a sewing machine;

said sewing machine including a reciprocal needle for stitching a seam in material advanced along a feed direction, and controls for operating said sewing machine;

means for driving said sewing machine;

said driving means including a variable speed motor with a shaft, an electromagnetic brake mounted on the motor shaft, and means for sensing rotation and angular displacement of the motor shaft;

means for counting stitches being sewn by said sewing machine;

a sensor mounted in spaced relationship ahead of said sewing machine needle for detecting the material edge following a seam;

a microprocessor controller operatively associated with said stitch counting means, sewing machine drive means, and sewing machine controls; said microprocessor controller having plural operational modes and being responsive to said material edge sensor and said motor shaft sensing means; said microprocessor controller being operable in one mode to record for each seam the operational sequence of said sewing machine controls as a function of stitch count, the sewing speed profile, and an adaptive number of terminal stitches between detection of the material edge by said sensor and the seam endpoint; and

said microprocessor controller in another mode being operable to generate output signals for said sewing machine controls and the brake of said driving means to initiate countdown of said adaptive number of terminal stitches upon detection of the material edge by said sensor, wherein said microprocessor controller in said another mode monitors the stitches sewn during deceleration of the sewing machine to a seam endpoint and adaptively adjusts the point at which deceleration is initiated in order to minimize the number of slow stitches at the end of each seam.

10. The semi-automatic sewing system of claim 9, further including:

auxiliary means for performing a predetermined function associated with operation of said sewing machine;

said microprocessor controller in said one mode further being operable to record the operational sequence of said auxiliary means as a function of stitch count; and

said microprocessor controller in said other mode further being operable to control said auxiliary means.

11. The semi-automatic sewing system of claim 9, wherein said sensor comprises an infrared emitter of variable sensitivity and an associated sensor located in spaced relationship ahead of said sewing machine needle.

12. The semi-automatic sewing system of claim 9, wherein said microprocessor controller in said one mode stores the total number of stitches required for each seam, and wherein said microprocessor controller in said other mode reverts to said total stitch count for determining seam length absent detection of the material edge by said sensor.

13. The semi-automatic sewing system of claim 9, wherein said microprocessor controller in said one mode also stores the toggle history of said sensor for each seam, with countdown of said adaptive terminal number of stitches in said other mode also being predicated upon correspondence of the sensed and stored sensor toggle histories.

14. The semi-automatic sewing system according to claim 9, wherein said microprocessor controller in said other mode further compares the adaptive number of stitches required to decelerate said sewing machine to a precise stop with the number of stitches remaining to be sewn in the seam and utilizes, as a basis for terminating the seam, the last toggle point of said sensor which

provides a sufficient number of stitches to decelerate and halt said sewing machine.

15. A semi-automatic sewing system, comprising:

a sewing machine;

said sewing machine including a reciprocal needle for stitching a seam in material advanced along a feed direction, and controls for operating said sewing machine;

means for driving said sewing machine;

said driving means including a variable speed motor with a shaft, an electromagnetic brake mounted on the motor shaft, and means for sensing rotation and angular displacement of the motor shaft;

means for counting stitches being sewn by said sewing machine;

a sensor mounted in spaced relationship ahead of said sewing machine needle for detecting the material edge following a seam;

a microprocessor controller operatively associated with said stitch counting means, sewing machine drive means, and sewing machine controls;

said microprocessor controller having plural operational modes and being responsive to said material edge sensor and said motor shaft sensing means;

said microprocessor controller being operable in one mode to record for each seam the operational se-

quence of said sewing machine controls as a function of stitch count, the sewing speed profile, and an adaptive number of terminal stitches between detection of the material edge by said sensor and the seam endpoint; and

said microprocessor controller in another mode being operable to generate output signals for said sewing machine controls and the brake of said driving means to initiate countdown of said adaptive number of terminal stitches upon detection of the material edge by said sensor;

said microprocessor controller being responsive to said needle position sensing means, and being further operable in said one mode to record the point in the relevant needle reciprocation at which each toggle of said material sensing means occurs; and

said microprocessor controller being further operable in said other mode to adaptively adjust said terminal number of stitches for each seam in accordance with the sensed point in the relevant needle reciprocation at which the seam-termination toggle of said material sensing means occurs in order to improve seam length accuracy.
